UNITED STATES PATENT OFFICE

138,359

DESIGN FOR A TOY OR THE LIKE

Meyer Rapaport, Chicago, Ill.

Application March 13, 1944, Serial No. 112,889

Term of patent 7 years

(Cl. D34—15)

To all whom it may concern:

Be it known that I, Meyer Rapaport, a citizen of the United States, residing at Chicago, in the county of Cook and State of Illinois, have invented a new, original, and ornamental Design for a Toy or the like, of which the following is a specification, reference being had to the accompanying drawing, forming part thereof.

Fig. 1 is a front elevational view of the toy showing my new design.

Fig. 2 is a side elevational view thereof.

Fig. 3 is a perspective view, with the handle broken off, for convenience of illustration.

I claim:

The ornamental design for a toy or the like, as shown.

MEYER RAPAPORT.
